UNITED STATES PATENT OFFICE.

EDWIN L. WHITE, OF NEW YORK, N. Y., ASSIGNOR TO J. H. WHITE MANUFACTURING CO., OF BROOKLYN, NEW YORK, A CORPORATION OF NEW YORK.

GAS-BURNER.

No. 922,989.

Specification of Letters Patent.

Patented May 25, 1909.

Application filed October 27, 1908. Serial No. 459,680.

To all whom it may concern:

Be it known that I, EDWIN L. WHITE, a citizen of the United States, residing at the borough of Brooklyn, in the county of Kings, city and State of New York, have invented an Improvement in Gas-Burners, of which the following is a specification.

As heretofore constructed, the gas burners of gas fixtures and the electric light fixtures of electroliers have each been resolved into substantially a uniform style as between which the electric light devices are the more artistic pleasing and acceptable, and while regular and symmetrical in their parts are in pleasing contrast to the supporting arm of the electroliers, whereas the parts of gas burners are substantially the same size with one another and with the supporting arm of the fixture. These latter parts are made of cast metal, with a finish and are more liable to discolor than are the polished and lacquered sheet metal parts of an electric light holder. Furthermore, with combination gas and electric fixtures the form of the gas burners and their glass-ware are in unpleasing contrast with the electric light fixtures and their glass-ware instead of in pleasing harmony and uniformity therewith, and the object of my invention is to clothe the gas fixture with a surrounding shell in simulation of harmony with the electric light devices which may be upon the same fixture so as always to be able to use uniform glass-ware and holders and to secure the most pleasing and ornamental effect.

In carrying out my invention I employ a two-part cylindrical shell surrounding and to be attached to the gas burner arm and receive the stem of the gas cock and expose the key to be grasped and turned by the hand. This cylindrical shell receives and supports the shade holder and the shade or globe. It incloses all of the gas burner but the tip end and in appearance is to be the same as electric light holders associated therewith. It may also inclose and support the base of a gas or electric candle either alone or in a combination fixture, and it is equally available in simulating an electric light fixture whether a gas globe, shade or candle is employed,—all of which is hereinafter more particularly described.

In the drawing, Figure 1 is a vertical section and partial elevation representing the device of my invention and Fig. 2 an eleva-

tion of the same without the shade or globe. Fig. 3 represents a modification, and Fig. 4 represents a combination bracket fixture showing my improvement employed with a candle effect.

a represents an arm of the fixture, *b* the gas pipe threaded at *b*¹ at its free end.

*a*¹ is a nut screwing upon the threaded end *b*¹ of the gas pipe and coming against the end of the fixture arm *a* to locate the parts and to form a base or support for the lower end of the cylindrical shell.

The gas cock *c* is as usual to be screwed upon the threaded end of the gas pipe, the same being provided with a stem *c*¹ and a finger button or knob *c*² for turning on or off the supply of gas.

d represents a sleeve and *e* the tip or burner at the upper end of the sleeve, said parts to be secured upon the upper end of the gas cock *c* as usual.

The arm *a*, gas pipe *b* with its threaded end, the gas cock *c*, the sleeve *d* and tip *e* are all of the usual and well known character in this art.

f represents a cylindrical cup-shaped shell curved and in-turned and centrally apertured to fit over the threaded portion *b*¹ of the gas pipe and to rest upon the nut *a*¹ screwed thereon. This cylindrical shell is off-set at 2 so as to provide an internal seat and I employ a clamping nut 3 coming within the shell and screwing upon the threaded end *b*¹ of the gas pipe so that between the nuts 3 and *a*¹ the cylindrical shell *f* is securely and centrally held at its apertured base.

I employ a cylindrical shell *h* of an external diameter agreeing with the internal diameter of the off-set portions of the cylindrical shell *f* so that the lower end of this cylindrical shell fits within the off-set portion and rests upon the shoulder 2 and is supported thereby. This cylindrical shell is provided with a slot *h*¹ to fit over the stem *c*¹ when the said shell *h* is connected to the shell *f*; the union of these two shells almost closing around the said stem.

The cylindrical shell *h* is preferably provided at or near its upper end with an annular bead *i*², and I provide a shade or globe holder *i* with arms *i*¹ which arms extend inwardly and downwardly and connect with a divided ring or band *l*, which is to be placed around the upper end of the cylin-

drical shell h below the annular bead i^2 and the same is held in place preferably by means of a screw m .

h represents a shade or globe which may 5 be of any desired form or material, the same being adapted for connection with and support by the said shade holder i .

It will be apparent from the foregoing 10 description and the illustration, that the cylindrical shells and the shade holder almost completely envelop and conceal the gas cock, its sleeve and tip, simulating an electric light socket and presenting thereby a pleasing appearance and contrast to the 15 size of the fixture arm a . This pleasing contrast is especially in evidence where these devices are employed on combination fixtures for the gas burners, as therein the gas burners and the electric globe holders or 20 sockets appear one and the same structure, and a casual observer would not detect which was the gas or which the electric light until the respective parts were lit and in operation; thus a far more pleasing appearance 25 is created and a more acceptable fixture than where there is a great and striking contrast which does and always must exist between the ordinary lamp socket and gas burner.

30 In the modification shown in Fig. 3, the upper end of the cylindrical shell h is made with a pressed screw thread h^2 and the shade ring i provided with arms i^1 is formed with a threaded ring i^3 to screw upon the threaded 35 part h^2 of the shell h . This provides a simple construction of detachable parts easily and cheaply made and assembled.

In the modification Fig. 4, a combination 40 bracket fixture is shown with a gas burner o bracketing a candle above the electric light device n ; the pipe p being provided with the cylindrical shells f h and the candle simulation o forming a continuation of the upper shell h and termination of this part 45 of the fixture. Where gas light brackets with candles are grouped with electric fix-

tures the cylindrical shell simulation is in harmony with the electric fixtures.

I claim as my invention:

1. The combination with the gas pipe of a 50 fixture, the gas cock and its key and the burner tip, of a two-part separable cylindrical shell of sheet metal surrounding the gas cock, the end of the gas pipe and part of the burner, one of said parts having an 55 integral holding portion formed at its free end and a slot for the key at the intersection or point of union of said parts, and the other of said parts having an off-set portion with a shoulder to receive and support the 60 other part of said shell.

2. The combination with the gas pipe of a combination gas and electric light fixture, the gas cock and its key and the burner tip, of a two-part separable cylindrical shell of 65 sheet metal surrounding the gas cock, the end of the pipe and part of the burner, one of said shell parts being cup-shaped, curved and in-turned and centrally apertured to fit over the threaded end of the gas pipe, a nut 70 screwed upon such threaded end of the gas pipe and upon which said cup-shaped shell part rests, a clamping nut within the said shell part and screwing upon the threaded end of the gas pipe so that between the two 75 said nuts the said cylindrical shell part is securely and centrally held at its apertured base, said shell part being off-set at its upper portion to provide an internal seat, and the other of said shell parts being of an external 80 diameter agreeing with the internal diameter of the off-set portion of said first shell part and fitting therein and resting upon the aforesaid seat and thereby supported, said second shell part having at its upper end 85 an integral means for receiving and holding a shade or globe support.

Signed by me this 8th day of October 1908.
EDWIN L. WHITE.
